UNITED STATES PATENT OFFICE

ANTON N. HORNUNG, OF LOS ANGELES, CALIFORNIA

LATCH ASSEMBLY FOR REFRIGERATOR DOORS

Application filed October 9, 1929. Serial No. 398,399.

This invention comprises an assembly applicable to refrigerator door latches of the character set forth in Letters-Patent No. 1,534,216 granted to me April 21, 1925.

5 An object of this invention is to provide means whereby a latch of the character set forth in said patent, can be delivered to the mechanic in fewer parts and can be applied to refrigerators and to refrigerator rooms, 10 cabinets and compartments with greater ease than with the device set forth in my said patent.

In the patented latch I provided a rock shaft with two bell-crank handles in angular relation and spread apart on opposite sides of the door to which the shaft was journaled by plates on opposite faces of the door, and in this invention the shaft and bell cranks are employed in much the same way 20 as in the patent; therefore detail illustration of the parts on the inner face of the refrigerator door is not deemed necessary in the present application.

Another object of this invention is to make 25 provision for adjusting the latch movement so as to avoid unnecessary lost motion.

Another object is to provide a construction and arrangement whereby the latch may be exactly adjusted to the strike and keeper.

30 Another object is to properly house the latch bolt and its operating adjuncts.

An advantage gained is time and labor saving in making an installation of the latch and its adjuncts.

35 A feature of the invention is construction whereby the latch bolt and the spring for shooting it into and holding it in position while passing the strike and keeper, and when coming to rest in latching position may be accurately adjusted, and whereby the operation will invariably be smooth and without jar or rattling.

A feature of the invention is that I provide 40 in combination with a floating bolt that is held by a spring toward latching position, a bolt retracting rod slidable relative to the floating bolt and connected to an operating handle and having a head to retract the floating bolt directly and practically without lost motion.

The invention includes the combination and parts thereof herein set forth, and I may embody the same in various forms without departing from the spirit thereof.

An object is to make provision whereby, although the latch is normally thrown into latching position by yielding means, the attendant may, by lifting up on the latch handle, force the latch into latched position.

Other objects, advantages and features of invention may appear from the accompanying drawing, the subjoined detailed description and the appended claims.

The accompanying drawing illustrates the invention.

Figure 1 is a fragmentary view from above showing the assembly partly in longitudinal mid-section installed on the door of a refrigerator, fragments of which, with some of the latch adjuncts in place are shown; the door being shown closed.

Fig. 2 is a perspective view of the latch bolt and its operating connection and spring as they appear when removed from the housing.

Fig. 3 is a fragmental elevation with parts in section on line x3, Fig. 1.

Fig. 4 is a vertical section on line x4, Fig. 3.

Fig. 5 is a rear view of the housing detached.

Fig. 6 is a rear end view of the housing detached.

Fig. 7 is a perspective view of the assembly in place on a refrigerator door closing past a strike and keeper on the jamb of a refrigerator fragmentally shown.

The housing comprises a shell 1 having an open back, and a panel 2 detachably fixed to the shell and closing the back to form a way 3 open forwardly and rearwardly as at 4 and 5 to accommodate a latch 6 slidable in the way, a latch advancing spring 7 and a latch retracting connection 8.

The shell comprises a face wall 9 that connects two side walls 10 which extend forwardly of the face wall 9 and which are provided with bearing extensions 11 that carry a roller composed of a roller axle 12, riveted in said bearing extensions, and a roller sleeve 13 journaled on the axle.

The base of the shell is provided with side flanges 14 having countersunk screw holes 15 through which anchor screws 16 are inserted to screw into the door 17 of the refrigerator to which the latch is thus fixed.

5 The face of the shell walls 10 are grooved as at 18 to form a seat for the panel 2 which is held in place by means of one or more panel retaining screws 19 screwed into threaded 10 sockets 20 in the bottoms of the side walls which are thickened by outside enlargements or bosses 21 to accommodate the panel screws 16.

15 The periphery of the roller 13 is in front of and flush with the inside of the face wall 9 to anti-frictionally support the protruding portion of the latch 6 when the roller 22 of the latch strikes the strike, keeper or catch 23 that is fixed to the door jamb 24.

20 The latch comprises two runners formed of side bars 25 spaced apart by two cross bars 26 and 27, the rearward one of which has a way 28 through which extends the connecting rod 8 that is threaded at its forward end 25 to screw into a retainer comprising a push nut 29, in front of which I have shown a draw nut 30, both of which nuts are non-rotatable within the space 31 formed between the side bars and cross bars.

30 The rear terminal of the rod that forms the connection 8 is formed with an eye 32 for a hinge pin 33 which hinges the connection to the latch retracting forks 34 of the latch handle 35 which is journaled by the shaft 36 35 in the escutcheon plates 37.

35 The notch 5 is wide enough to allow the eye 32 to pass therethrough and a washer 38 that will not pass the eye or pass flatwise through the notch, is slipped on to the connecting rod 40 before it is inserted into the bolt and when the rod has been inserted through the rear cross-bar 26 and screwed into the nuts, the workman may insert the latch 6 through the front end of the housing, and the eye 32 45 through the notch, compressing the spring against the washers 38 held by the notched rear wall of the housing, and the hinge pin 33 is then inserted and the latch is ready for installation in the door in an obvious manner.

50 As the door closes, the roller running over the keeper is forced back and may compress the spring without thrusting the handle, because the latch is slidable at first independently of the connecting rod, and when the 55 roller has passed the keeper the stop bar 26 comes snug against the rear face of the draw nut 29; thus the spring holds the parts in the position shown in Fig. 3 until it is desired to unlatch the door; then the attendant may 60 depress the handle, thus at once retracting the latch without lost motion.

By properly locating the nut 29, the latching roller 22 can be accurately adjusted relative to the strike 23 so that when the parts 65 are at rest as indicated in Figs. 1 and 3, the

axis of the pin 39 will have passed beyond a line indicated at $a-a$ extending from the catch lip 41 at right angles to the latch body so that compression of the resilient packing 42 is maintained by the latch, and the latch 70 cannot be retracted except by pressure along its length.

By this arrangement the adjustment can be so exact that a very slight retraction of the latch allows the roller to be rolled back 75 by the catch.

In case from any cause the latch should work hard and not fully seat in the keeper, the handle may be lifted thus causing the push nut to force the latch roller forward. 80

The fork 34, and handle, 35, are arranged relative to the shaft 36, and the connection 8, when the spring is in place as indicated in Fig. 3, so that the handle 35, will overhang the pin 33, and a downward movement of the 85 handle 35 will cause the draw nut 30 to retract the roller 22; so that the upward pressure of the handle 35 will cause the push nut 29 to shove the aboutment 26 and the latch forward, thus to force the roller into the 90 latching position shown in Fig. 1.

I claim:—

1. In a latch, a housing having a latchway open forwardly and rearwardly and having side walls spaced apart and provided in their faces with panel seats and threaded sockets for panel securing screws provided with bearing extensions having holes for anchor screws; a latch arranged with its body slidable in the latchway and its latching end extended forwardly beyond the housing; a spring in the housing to yieldingly hold the latching end of the latch fully extended; latch retracting means connected to the latch and extending through the rearward opening; a roller mounted in the bearings and extending peripherally into the slide way to form an antifriction support for the latching end of the latch; a panel in the panel seats and screws in the sockets to hold the panels 100 in the panel seats. 105

2. The combination of a channel latch housing adapted to be fixed to a door and having an abutment connecting the side walls 115 and extending across the slideway at the other end; of a latch member comprising two runners spaced apart and an abutment connecting the runners between their ends and providing therewith two nut seats; nuts non-rotatable in said seats; a rod slidable through the housing abutment, screwed through one of said nuts, extended through the latch abutment and screwed through the other nut; and a spring between the first nut and the housing abutment. 120

In testimony whereof, I have hereunto set my hand at Los Angeles, California, this 19th day of September, 1929.

ANTON N. HORNUNG.
